CIRCUIT BREAKER

Stephen S. Grady, Magnolia, N. C., assignor to
Fusoid Electric Co., Inc., a corporation of New
York

Application April 30, 1931, Serial No. 533,949

11 Claims. (Cl. 200—106)

This invention relates to circuit breakers and with regard to its more specific features to such devices adapted for the protection of electric circuits against excessive currents.

5 One of the objects of the invention is to provide a device of the above nature practical and efficient and capable of meeting the requirements of use in a highly satisfactory manner. Another object is to provide a device of the above nature 10 simple in construction and at all times dependable in action. Another object is to provide a mechanical circuit breaker adapted to take the place of cartridge fuses and co-act in an efficient manner with the standard mountings provided 15 therefor. Another object is to provide such a device conveniently adjustable to the varying conditions of practical use. Other objects will be in part obvious or in part pointed out herein-after.

20 The invention accordingly consists in the features of construction, combinations of elements, and arrangements of parts as will be exemplified in the structure to be hereinafter described and the scope of the application of which will 25 be indicated in the following claims.

In the accompanying drawing in which are shown one or more various possible embodiments of the several features of this invention.

Figure 1 is a side elevation of a circuit breaker, 30 parts being cut away to better disclose the structure.

Fig. 2 is an end view looking toward the left-hand end of Figure 1.

Fig. 3 is a view similar to Fig. 2 showing a 35 slightly modified form, and

Fig. 4 is a sectional view of another modification.

Similar reference characters refer to similar 40 parts throughout the several views of the drawing.

Referring now to the drawing, in detail, there is shown in Figure 1 a pair of metallic members shaped to provide parts 10 and 11 respectively of rounded contour as shown in the end view of 45 Figure 2. The part 10, as shown in this figure, terminates in lateral flanged portions 12 and 13 and a pair of up-standing ears 14, the part 11 being shaped in a similar manner and providing a similar pair of ears 15. These parts are formed 50 of a suitable conducting metal and are rigidly connected together by a member 16 of insulating material which is secured to the flanged portions 12 and 13 of the part 10 and to corresponding flanged portions of the part 11. These rounded 55 parts 10 and 11 are so shaped and are so spaced by the member 16 as to fit into and co-act with the standard cut-outs or fuse clips which are made to receive cartridge fuses of standard design and size. The spring clips of such a standard fuse mounting are represented at 17 and 18

with the members 10 and 11 respectively coating therewith in operative position. It may be here noted that the usual cartridge fuse mountings are made according to different standard designs for cartridge fuses of different current capacities and that such mountings will be hereinafter referred to generally as standard fuse mountings. It will be seen that the parts 10 and 11 are conveniently slipped into place in the clips 17 and 18, in place of the usual rounded end portions 10 of the ordinary cartridge fuse.

Opposite the member 16 is a member 19 of insulating material to which is secured, opposite the ears 14, a member 20 provided with a pair of depending ears 21. The ears 21 are adapted 15 to co-act with the ears 14 as shown in Figure 2 and make electrical connection therewith. Adjacent the other end of the member 19 is secured a member 22 similar to the member 20 and provided with a pair of depending ears 23. The 20 ears 23 make electrical contact with the ears 15 of the part 11 and are pivoted thereto as by a pin 24. The member 19 therefore and the parts connected therewith are capable of swinging 25 about the pin 24, the ears 21 thereby moving into or out of electrical contact with the ears 14.

Carried by the member 19 is a solenoid winding 25 connected by conductors 26 and 27 with the ears 21 and 23 respectively. Therefore when the member 19 with its connected parts is swung 30 downwardly as viewed in Figure 1 so that the parts 21 and 14 are in contact, the circuit is complete from the fuse clip 17 through the solenoid 25 to the fuse clip 18, and when the member 19 is swung to the position shown in Figure 35 1 the circuit is broken.

A flat spring 28 urges the member 19 and the parts carried thereby to swing outwardly to the position shown in Figure 1. Overhanging the 40 left-hand end of the member 19 is a latch member 29 adapted to co-act with a latch member 30 to hold the parts in the position shown in Figure 2 against the action of the spring 28. The latch member 30 is suitably secured to the members 16 and 10, for example, as at 31 and 32. The latch member 29 terminates at its upper end in a rounded portion 29a resting upon the upper surface of the member 19 and through an enlarged opening in which passes a screw 33 threaded into the head of the member 19. Between the head of the screw 33 and in part 29a is a compression spring 34. The spring 34 thus tends to hold the latch member 29 in the position shown in the drawing, but upon movement of the lower part of the 50 member 29 outwardly to disengage the latch member 30 the part 29a rocks upon the surface of the member 19. Passing through the center of the solenoid 25 is a rod 35 preferably of brass or other suitable non-magnetic substance which is supported at one end by a bracket 36 secured 55

to the member 19, and at the other end by the latch member 29 through which it passes. The rod 35 is provided with a shoulder 37 which limits its movement to the right through the bracket 36 and is also provided with a shoulder 38 abutting the latch member 29. Upon the rod 35 is provided a member 39 of iron which is adapted to be attracted by the magnetic field of the solenoid 25. The right-hand end of the rod 35 is threaded and between the nut 40 thereon and the bracket 36 is a compression spring 41 which thus acts in opposition to the pull of the solenoid 25 upon the part 39 and the rod 35. The movement of the rod 35 to the left therefore, under the urge of the solenoid 25 or otherwise, through the shoulder 38, will release the latch member 29 from engagement with the catch 30, thus permitting the spring 28 to swing the parts to the position shown in Figure 1, thus breaking the circuit. Considering now the action of the apparatus, when the parts are in position of engagement as shown in Figure 2, current will flow between the fuse clips 17 and 18 through the solenoid 25. The parts are so proportioned that when the current flowing exceeds a predetermined value the pull of the solenoid 25 is sufficient to draw the part 39 inwardly against the action of the spring 41. The predetermined current at which this action takes place may be regulated or adjusted by adjustment of the compression in the spring 41. Such movement of the part 39 through the rod 35 moves the latch member 29 from engagement with the catch 30 and the spring 28 is free to swing the parts out of engagement to the position shown in Figure 1. The ears 21 and 14 therefore being out of engagement, the circuit is broken. Thus the circuit is automatically protected from the danger of excessive flow of current and the value of the current at which the device will trip may be adjusted. In order to insure further protection, if desired, a fuse 42 may be inserted in series with the solenoid, the fuse 42 being adapted to blow at a slightly higher current than that at which the solenoid is set to move the rod 35.

The circuit breaker may be operated manually at any time if so desired, substantially taking the place of an extra switch. The circuit may be broken manually by simply pushing the rod 35 to the left by a thrust on its projecting right-hand end, or the part 29a of the latch may be rocked to release the catch. In order to reset the circuit breaker, it is necessary to simply push the member 19 inwardly until the latch is again in engagement. The circuit breaker may thus be operated manually for either making or breaking the circuit in a highly convenient manner without removing the device or in any way interfering with its mounting upon the fuse clips 17 and 18. Furthermore, the position of the parts at all times clearly indicates whether the circuit is complete or broken.

The larger sizes of standard make cartridge fuses are made with knife-blade contacts instead of the rounded contacts and the standard mountings or fuse clips are accordingly made to receive these knife-like blades. A standard fuse mounting of this type is represented at 43 in Figure 3. In order to co-act with this mounting the device above described in connection with Figures 1 and 2 is provided with knife-blade contacts 45 instead of the rounded contact members 10 and 11. As is shown in Figure 3 the member forming the contact ears 14 is provided with a lateral portion 44 from the opposite side of which projects

the knife-blade 45. It is to be understood of course that, in this instance, the member forming the ears 14 at the other end of the device, is correspondingly shaped.

Referring now to Figure 4, there is shown an embodiment of this invention adapted to co-act with a different type of standard fuse mounting, namely one adapted to receive a standard cartridge fuse ordinarily known as a plug fuse. As is well known these plug fuses are threaded into a standard fuse mounting comprising a socket, the threads of the plug fuse making one contact and a member at the inner end of the plug making the other contact. In Figure 4 there is shown an insulating plug 46 about which is a threaded metallic sleeve 47 adapted to fit the threads of a standard plug fuse mounting. At the end of the member 46 is a contact 48 serving as the other contact to make connection with the socket. The plug member 46 is hollow and mounted therein is a solenoid 49 connected as will presently be described.

The plug member 46 is joined to an annular member 50 also of insulating material. Secured to this member 50, as at 51 and 52, is a pair of oppositely disposed metallic members 53 and 54 respectively. These members 53 and 54 are of a suitable conducting metal of resilient properties, and projecting upwardly to the interior of the annular member 50, they tend to spring inwardly toward each other. Between these two contact springs 53 and 54 is gripped a member 55 of insulating material normally projecting from the interior of the annular member 50 as shown. This member 55 is provided with an annular groove in which rests an annular conducting strip 56. The spring contacts 53 and 54 are provided with inwardly directed projections 53a and 54a respectively which normally extend into the annular groove in the member 55 making contact with the conducting strip 56 therein. The strip 56 therefore normally makes electrical connection between the spring contacts 53 and 54 and the spring contacts serve to yieldingly hold the member 55 in the position shown in the drawing.

Passing through the member 55 and threaded therein is a rod 57 preferably formed of brass or other suitable non-magnetic substance which extends downwardly through the solenoid 49 and is provided at its lower end with a member 58 of iron. The member 58 therefore is adapted to be drawn inwardly by the solenoid 49 thus carrying the rod 57 and the member 55 upwardly against the action of the spring contacts 53 and 54. The solenoid 49 is connected at one end to the contact member 48 as by a conductor 59 and at the other end to the spring contact 53 as by a conductor 60. The other spring contact 54 is connected as by a conductor 61 with the contact sleeve 47.

With the parts in normal operative position, as shown in the drawing, the circuit is thus completed from the contact member 48 through the solenoid 49 to the contact sleeve 47. In the action of the device when the current through the solenoid 49 exceeds a predetermined value the member 58 is drawn inwardly by the pull of the solenoid. Such movement through the rod 57 carries the member 55 outwardly against the action of the spring contacts 53 and 54 engaging the annular groove therein. This results in breaking the contact between the annular strip 56 and the projections 53a and 54a so that the circuit is broken. The rod 57 is preferably provided

with a screw head 62 positioned in a recess in the top of the member 55 so that the rod 57 may be conveniently threaded in or out of the member 55 thus changing the normal position of the iron member 58 with respect to the solenoid. 5 In this manner the value of the current at which the solenoid will draw the member 58 upwardly against the action of the springs 53 and 54 may be conveniently adjusted. The circuit is thus 10 automatically protected against currents in excess of a predetermined value.

After the device has been tripped as above described, it is conveniently reset without removing the same from the fuse mounting by simply 15 pushing the member 55 back into place. Furthermore, the device may be operated manually at any time to break the circuit, it being necessary to simply grasp the projecting member 55 and draw it outwardly. The position of the part 20 55 indicates at all times whether or not the mechanism is in circuit closing position.

From the above it will be seen that there is herein provided apparatus which embodies the several features of this invention and attains the 25 objects thereof and that the apparatus is well adapted to meet the requirements of practical use. The mechanisms are simple in construction, at all times dependable in action and attain many practical and useful advantages.

30 It will also appear that by means of the present invention, see the embodiment illustrated in Fig. 1, when the device is used with a circuit of alternating current that when an over-load occurs so that the current in the solenoid winding 25 35 attracts the core 39, the inductive reactance thereby established will automatically break the current even though the latch member 29 did not clear the latch member 30 and the spring 28 thereupon did not raise the bracket 19 to cause 40 the contact between the contacts 21 and 14 to be broken.

In other words, the induction produced in the solenoid winding 25 not only initiates the mechanical interruption of the circuit by actuation 45 of the plunger 35 in turn to actuate the latch member 29 to permit the spring 28 to raise the bracket 19 but in addition thereto also electrically interrupts the current due to the inductive reactance set up when the core 39 is moved into 50 the winding 25.

It will also appear that, by means of this device, due to the fact that the current may be 55 electrically interrupted by the inductive reactance produced when the solenoid winding 25 attracts the core 39, the subsequent separation of the contact 21 from the contact 14 will occur when the current has already been broken so that arcing between the contacts 21 and 14 will be eliminated, if the current is so interrupted by 60 the inductive reluctance before the plunger 35 has had an opportunity to free the latch member 30 from the latch member 29 by co-operation with the spring 28.

As many possible embodiments may be made 65 of the above invention and as many changes might be made in the embodiment above set forth, it is to be understood that all matter hereinabove set forth is to be interpreted as illustrative and not in a limiting sense.

70 I claim:

1. In apparatus of the class described, in combination, a pair of members removably coacting with a pair of standard fuse clips and each having exterior of said clips a lateral flange portion 75 extending over the outer edge of said clips, a

rigid base member of insulating material secured upon said flange portions and positioned thereon exterior of the outer edges of said clips, connecting said members together and holding the same in fixed relation to coact with said fuse clips, a 5 mechanically operated switch connecting said two members, and means adapted to open said switch upon current of predetermined value flowing therethrough, said switch being adapted for manual closing with said members remaining in 10 operative position in said fuse clips.

2. In apparatus of the class described, in combination, a member adapted to coact with one of a pair of standard fuse clips, formed of sheet metal and having a part adapted to enter said 15 fuse clips and a pair of upstanding ears projecting outwardly therefrom, a second member adapted to coact with the other of said pair of fuse clips, a switch member electrically connected with said second member and having a part 20 adapted to slide into position between and bear outwardly against said pair of ears and to move into and out of engagement therewith to make and break electrical connection between said two members, and means adapted to move said part 25 of said switch mechanism out of engagement with said upstanding ears upon current of predetermined value flowing therethrough.

3. In apparatus of the class described, in combination, a rigid base member of insulating material, a pair of members mounted thereon and adapted respectively to coact with a pair of standard fuse clips, a pair of upstanding ears 30 electrically connected with one of said members, a second pair of upstanding ears electrically connected with the other of said members, a switch member having one end pivoted upon one of said 35 pair of ears by a pivot pin passing through said ears and adapted to swing thereon and having a part adjacent the other end thereof adapted to 40 slide into and out of position between and in engagement with the other of said pairs of ears to make and break electrical connection between said pair of members coacting with said fuse clips, and means adapted to open said switch upon current of predetermined value flowing 45 therethrough.

4. In apparatus of the class described, in combination, a rigid base member of insulating material, a pair of contact members mounted upon 50 said base member and adapted respectively to coact with a pair of standard fuse clips, an upstanding metal part adjacent one end of said base member electrically connected with one of said contact members, a second upstanding metal 55 part adjacent the other end of said base member and electrically connected with the other of said contact members, an arm of insulating material having adjacent each end thereof a projecting metal part adapted respectively to 60 engage said two upstanding metal parts on said base member and make electrical connection therewith, conducting means between said two projecting metal parts of said insulating arm, means pivotally connecting one of said projecting 65 metal parts to said upstanding part on said base member with which it engages, and means adapted upon current of predetermined value flowing through said conducting means to swing said arm about its pivot and move said other projecting 70 metal part thereon out of engagement with its corresponding upstanding metal part on said base member.

5. In apparatus of the class described, in combination, a rigid base member of insulating ma-

5. A pair of members thereon adapted respectively to coact with a pair of standard fuse clips, a switch interposed between said two members, means urging said switch toward open position, a latch adapted to restrain said first means, a spring holding said latch in restraining position, electro-magnetic means adapted to act in opposition to said spring and to release said latch upon flow of current of predetermined value, and 10 means for adjusting said spring to adjust the opposition to said electro-magnetic means, said adjusting means being accessible and operative with said pair of members in operative position in said fuse clips.
15. 6. In a circuit breaker for an electric circuit of alternating current, the combination with two terminals in the main line of the circuit, of a bracket pivotally connected to one of said terminals, a fixed latch member secured to the 20 other terminal, a movable latch member at the end of said bracket, a solenoid winding mounted on said bracket and electrically connected in the main line of the circuit and to said terminals when said latch members are in locking engagement, a spring urging said bracket into latch breaking position, a non-magnetic plunger mounted on said bracket to actuate the latch member on said bracket; and a soft iron core 25 on said plunger normally disposed outside of said winding to be attracted by the winding when an overload occurs to build inductive reactance to break the current electrically and to cause said plunger to actuate said movable latch member to permit said spring to actuate said bracket to 30 interrupt the current.
7. In a circuit breaker for an electric circuit of alternating current, the combination with two terminals in the main line of the circuit, of a bracket pivotally connected to one of said terminals, a fixed latch member secured to the other 35 terminal, a movable latch member at the end of said bracket, a solenoid winding mounted on said bracket and electrically connecting said terminals in the main line of the circuit when said latch members are in locking engagement, a spring urging said bracket into latch breaking position, a non-magnetic plunger mounted on said bracket to actuate the latch member on said bracket; and a soft iron core 40 on said plunger normally disposed outside of said winding to be attracted by the winding when an overload occurs to build inductive reactance to break the current electrically and to actuate said movable latch member to permit said spring to actuate said bracket out of engagement with said other terminal.
8. In a circuit breaker for an electric circuit of alternating current, the combination with two terminals in the main line of the circuit, of a frame pivotally connected to one of said terminals; a fixed latch member secured to the other 45 terminal; a movable latch member at the free end of said frame adapted to cooperate with said fixed latch member to anchor said frame in circuit making position; a spring urging said frame into latch breaking position; and means for actuating said movable latch member into latch breaking position when an overload occurs consisting in a solenoid winding electrically connected to one of said terminals, a plunger slidably 50 mounted in said solenoid, and a soft iron core on said plunger normally disposed outside of said
- winding to be attracted by the winding when an overload occurs to build inductive reactance to interrupt the current electrically and to cause said plunger to actuate said movable latch member into latch breaking position to permit said spring to actuate said frame out of engagement with said other terminal.
9. In a circuit breaker for an electric circuit of alternating current, the combination with two terminals in the main line of the circuit; of a movable frame; an electrical conductor mounted on said frame; resilient means for anchoring said frame in position to bridge said two terminals by said electrical conductor; and means for moving said frame into position to interrupt the current 15 across said conductor when an overload occurs including a solenoid winding electrically connected to one of said terminals in the main line, a plunger mounted on said frame and slidably in said solenoid winding, and a soft iron core on said plunger normally disposed outside of said winding to be attracted by the winding when an overload occurs to build inductive reactance to interrupt the current electrically and to cause said plunger to overcome the resilient connection between said resilient means and said frame and thereby to release said frame into circuit breaking position.
10. In a circuit breaker for an electric circuit of alternating current, the combination with two 20 terminals in the main line of the circuit; of a movable frame; a conductor mounted on said movable frame; a spring finger connected to each of said terminals and positioned to engage said conductor and anchor said frame in circuit making position; and means for actuating said frame into finger releasing position and thereby circuit breaking position consisting in a solenoid winding connected to one terminal in the main line, a plunger mounted on said movable frame 25 and slidably in said winding, and a soft iron core on said plunger normally disposed outside of said winding to be attracted by the winding when an overload occurs to build inductive reactance to break the current electrically and to engage said frame out of engagement of its conductor by said spring fingers and thereby into circuit breaking position.
11. In a circuit breaker for an electric circuit of alternating current, the combination with two 30 terminals in the main line of the circuit; of a movable frame consisting of a tapered plug composed of insulating material and having an annular recess; an electrical conductor in said recess; a spring finger connected to each of said terminals and positioned to enter said recess resiliently to anchor said plug and to contact said conductor in circuit making position; and means for actuating said frame into finger releasing position and thereby circuit breaking position consisting in a solenoid winding connected to one 35 terminal in the main line, a plunger mounted on said movable frame and slidably in said winding, and a soft iron core on said plunger normally disposed outside of said winding to be attracted by the winding when an overload occurs to build inductive reactance to break the current electrically and to actuate said frame out of engagement of its conductor by said spring fingers and thereby into circuit breaking position.

STEPHEN S. GRADY.
